UNITED STATES PATENT OFFICE.

DAVID L. WINTERS, OF EDGEWATER, MARYLAND.

CARBURETOR.

Application filed October 15, 1919. Serial No. 330,797.

To all whom it may concern:

Be it known that I, DAVID L. WINTERS, a citizen of the United States, residing at Edgewater, in the county of Anne Arundel 5 and State of Maryland, have invented certain new and useful Improvements in Carburetors, of which the following is a specification.

This invention relates to carburetors and 10 the method of operation wherein the fuel control valve and the throttle valve are operated simultaneously to control the flow of fuel and air and to maintain the relative proportions thereof and more particularly to that class of such devices adapted 15 for use with the motors of self propelled vehicles and it has for its primary object the provision of a carburetor so constructed as to operate to provide such motors at 20 all times with the minimum amount of fuel and the maximum amount of air which can be utilized to develop the required power necessary to varying conditions of operation.

25 A further object of this invention is to so construct a device of the character set forth wherein a very lean charge is normally fed therethrough and a proportionately richer mixture presented with relation 30 to the load, such proportionate increase being continued after reaching the point where a further opening of the throttle fails to produce the desired increase in speed; that is, when the throttle valve has 35 been opened to a point where its further opening will not be accompanied by an increased consumption of air in proportion to the increased consumption of fuel.

With the foregoing and other objects in 40 view as will hereinafter appear this invention consists in the peculiar combination and arrangement of the various co-operating elements of a carburetor as described in the following specification and more particularly pointed out in the appended claims.

45 Reference being had to the accompanying drawings illustrating an embodiment of the device, and in which the same numerals indicate the same parts wherever used,

50 Fig. 1 is a vertical section through a carburetor embodying the invention.

Fig. 2 is a top plan view thereof.

Fig. 3 is an enlarged section on line 3—3 of Fig. 1 and

Fig. 4 is an enlarged section on line 4—4 of Fig. 1.

5 designates the float chamber provided interiorly with a float 6 surrounding a central casing 7 extending upwardly to form the air intake 8, the intake 9 connecting 60 with the motor and having flanges 10 and 11 integral therewith which form a seat for the Venturi tube 12.

The usual butterfly throttle valve 13 is provided having a shaft 14 carrying an 65 operating lever 15 and a second lever 16 connected to a toggle member 17 in turn connected to an arm 18 carried by a collar 19 frictionally mounted upon a tube 20 in threaded engagement for a portion of its 70 length with the interior of a second tube 21 and extending therewith, the lower portion of the tube 20 being spaced from the tube 21 to leave an annular chamber 22 between the tubes.

75 Tube 21 is threaded into the member 7 at 23 and extends below the same to carry a cap 24 provided with a port 25 communicating with the interior of the tube 21 and a well 26 fed from the float chamber 5 by 80 a pipe 27 suitably packed at 28 and having a nipple 29 engaging the cap 24.

A drain plug 30 extends from the well 26.

Adjacent the Venturi tube 12 the tube 21 is provided with a plurality of diametri- 85 cally disposed ports 31.

The tube 20 has a central bore throughout, open to the air at its upper end 33 and closed by a plug 34 at the lower end thereof formed as a needle valve 35 extending into the port 25 and governing the same. Above the plug 34 in the tube 20 are a plurality of diametrically disposed ports 36 of larger diameter than the ports 31 for a purpose hereinafter described.

90 A second collar 37 carries an operating means 38 which is adapted to give the tube 20 a slight turning movement to cause the same to move up and down in the threaded portion 39 of the tube 21.

95 Air intake 8 is provided with an interior block 40 which is adapted to cooperate with a butterfly valve 41 carried by a shaft 42 which projects at 43—44 on either side of the exterior of the intake, the projection 43 having a spring 45 fastened to the intake 8 by a screw 46, the projection 44 being similarly provided with a stronger spring 47,

which engages the pin 48 only when the valve 41 is closed, thus forming a stop for the spring 45, and permitting the valve to open in the opposite direction in the event 5 of a back fire through the carburetor.

In the construction illustrated when the device is used in conjunction with a motor of the type specified suction is set up in the intake of the motor in the usual manner, 10 causing a like suction in the intake 9 and the Venturi tube 12, which tube is fed with fuel through ports 31 in tube 21 by the said fuel oil rising in the chamber 22, through the port 25, the well 26, pipe 27, from the 15 source of supply, to float chamber 5.

The necessary air for carburetting the fuel oil is drawn in through the opening 33 into the central bore of the tube 22 and passes outwardly therefrom through the ports 36.

20 The operating mechanism for the throttle butterfly 13 being connected by means of the levers 16 and 18 and link 17, as in my prior Patent 1,286,474, Dec. 3, 1918, with the collar 19 carried by the tube 20, upon opening 25 the throttle valve the collar 19 is rotated, causing the tube 20 to ride upwardly along the screw threaded portion 39, carrying with it the plug 34 and thus increasing the fuel 30 delivery capacity of the port 25. Upon the throttling of the engine or the closing of the valve 13 the reverse action is given to the levers and the needle valve 35, thus diminishing the supply of fuel drawn from the port 25.

35 Adjustment independent of the operation of the throttle valve 13 may be accomplished by operation of the means 38 which can conveniently extend to a point near the driver's seat, so that by a slight rotation of the collar 37 the relation between the tubes 20 and 40 21 may be varied along the screw threaded portion 39, in order to correspondingly vary the control of the needle valve 35 of the port 25.

45 The air intake 8 supplies air to the carburetor while volatilizing fuel in the usual manner in the cooperation with the float chamber 5 with the exception that the amount of air drawn through said intake 50 depends upon the suction through said intake, due to the fact that the valve 41 is normally closed and operates to open only upon suction exerting a pull thereagainst, such opening being made possible by the 55 construction of the flange with the block 40 which gives a valve of greater area upon one side, the closing of such valve being occasioned by the spring 45, which acts to retard the opening of the valve against suction, or to perform the closing operation 60 thereof, when such suction is discontinued by the stopping of the motor.

It will thus be seen that the carburetor is provided with two air passages, one of which 65 is of approximately the same relative di-

ameter as the intake connecting with the engine, and the other of which is of greatly reduced diameter. The air inlet of reduced diameter by discharging air beneath the level of the gasoline in the chamber 22 serves 70

to prime the motor when starting the same and to maintain while the motor is in operation a fixed gravity head between the float chamber 5 and the chamber 22 without regard to the variations in speed and load. 75

This is due to the fact that the air entering the open upper end of the tube 20 and flowing down through the same lowers the gasoline in the well to the level of the opening 36, and as the area of these openings is col- 80

lectively much greater than that of the openings 31 the volume of entering air is therefore comparatively unrestricted, while the outlets 31 for the mixture of air and gas are restricted. Therefore no suction will take 85 place on the valve opening 35. The larger air intake being slightly restricted by valve 41 insures the induction of enough air through air passage 33 to insure the use of all the fuel oil that the gravity head is capable of forcing through the needle valve 35.

As the area of the openings 31 is very much less than at 36, it will be understood from the foregoing that the smaller air passage effectually prevents suction on the fuel 90 below the point where the air is discharged into the chamber 22, thus permitting the maintenance of a fixed pressure or gravity head regardless of load conditions. As the fuel oil under any fixed position of the throttle is supplied and measured on a relative 95 timed basis only it will follow that any increase in load without change in position of the throttle will be accompanied by a corresponding decrease in speed, and as such reduction of speed also reduces the suction and consumption of air without affecting the consumption of fuel, the density of the mixture of fuel oil and air fed to the engine is increased in proportion to the effect of the 100 increase in load upon the speed of the motor, any decrease in load under the same conditions resulting in a correspondingly increased speed, and therefore the use of more air and a leaner mixture, such proportion being taken care of by the construction of the carburetor in accordance with my invention.

105 Considerable variation of the details as described herein may be resorted to without departure from the spirit of the invention 110 which is to be construed in the light of the following claims.

Having thus described my invention what I claim as new and desire to secure by Letters Patent is:

115 1. In a carburetor, in combination, a fuel inlet and control valve therefor, a throttle valve, means to simultaneously actuate said valves to maintain the relative proportions 120 of fuel and air, and means comprising con- 125

stantly open ports of fixed area greater than said fuel inlet to maintain a relatively fixed fuel flow head by means of a fixed gravity head, whereby to supply a richer or leaner 5 mixture in proportion to variations in the air flow head as effected by variations in the load on the engine.

2. In a carburetor, in combination, a fuel inlet and control valve therefor, a throttle 10 valve, means to simultaneously actuate said valves to maintain the relative proportions of fuel and air, and means to maintain a relatively fixed fuel flow head by means of a fixed gravity head comprising an air passage, constantly open ports of fixed area and a combined fuel and air passage opening through one of said ports into said air passage, said last referred to port being of greater area than said fuel inlet, whereby to 15 supply a richer or leaner mixture in proportion to variations in the air flow head as effected by variations in the load on the engine.

3. In a carburetor, in combination, a fuel 25 inlet and control valve therefor, a throttle valve, means to simultaneously actuate said valves to maintain the relative proportion of fuel and air, and means to maintain a relatively fixed fuel flow head by means of a 30 fixed gravity head, comprising an air passage, constantly open ports of fixed area and a combined fuel and air passage opening through one of said ports into said air passage, the outlet from the combined fuel and

air passage being of a restricted area relative to the air inlet therefor but greater than the fuel inlet, whereby to supply a richer or leaner mixture in proportion to variations in the air flow head as effected by variations in the load on the engine. 35

4. In a carburetor, in combination, a fuel inlet and a control valve therefor, a throttle valve, means to simultaneously actuate said valves to maintain the relative proportions of fuel and air, a fuel reservoir, means to 40 maintain fuel in said reservoir above the level of said fuel valve, an air passage, a tube extending from said fuel control valve to said passage, constantly open ports from said tube into said passage, an air tube extending within and concentric with said first named tube, constantly open ports in said air tube adjacent said fuel control valve, said last named ports being of greater area than said first named ports and said first 45 named ports being of greater area than said fuel inlet whereby a fixed gravity head for flow of fuel through said control valve will be maintained, whereby to supply a richer or leaner mixture in proportion to variations 50 in the air flow head as effected by variations in the load on the engine. 55

In testimony whereof I affix my signature in the presence of two witnesses.

DAVID L. WINTERS.
